BOILER FEEDER

James D. Jordan, Oak Park, and Daniel F. Ellis and Cecil W. Preston, Chicago, Ill., assignors to General Household Utilities Company, Chicago, Ill., a corporation of Delaware

Application September 4, 1937, Serial No. 162,563

12 Claims. (Cl. 62—115)

The present invention relates in general to the delivery of fluid into a chamber or container under relatively high pressure from a source or reservoir at lower pressure, and the invention 5 has more particular reference to boiler feed apparatus, and while the invention is especially adapted for the delivery of liquid in the boiler of refrigerating apparatus of the character illustrated and described in the co-pending application 10 of William C. Grunow et al. for United States Letters Patent, Serial No. 144,346, filed May 24, 1937, the present invention is not necessarily restricted to use in conjunction with refrigerating apparatus, but may have general 15 application.

An important object of the invention is to provide simplified means for feeding liquid into a container, such as a boiler, from a supply source which is at a relatively lower pressure, the invention 20 relating more particularly to the provision of simplified means having a minimum number of moving parts whereby the same does not readily get out of order in service.

Another important object is to provide a boiler 25 feed device operable in conjunction with the condenser of a refrigerating system and a boiler providing vapor under pressure for the actuation of jet pumps for causing circulation of a refrigerant in the refrigerating system in order to 30 deliver liquid from the condenser into the boiler against the relatively high pressure maintained therein during the operation of the system.

Another object is to accomplish the delivery 35 of a boiler feed medium by instantaneously evaporating a predetermined quantity of the medium at intervals to generate pressure in excess of that prevailing in the boiler and utilizing such generated pressure to force the remainder of the boiler feed medium into the boiler.

Another important object is to provide boiler 40 feed means comprising a chamber having valved connection with the boiler and with a low pressure source of supply whereby the boiler feed medium may be delivered into said chamber 45 from said source at a predetermined rate through a check valve, including means operable after a predetermined quantity of the medium has thus been introduced into the chamber, to cause sudden evaporation of a portion of the medium to 50 generate in said chamber a pressure sufficient to force the rest of the medium from the chamber through a check valve and into the boiler.

Another important object is to provide a vaporizing chamber, the walls of which are of substantial mass, having an appreciable heat stor-

age capacity, including means to continuously heat the walls and maintain the same at a temperature such that upon delivery of a predetermined quantity of the boiler feed medium into the vaporizing chamber the medium so delivered will be quickly vaporized; a further object being to connect the vaporizing chamber with a liquid delivery chamber adapted to receive substantial quantities of the feed medium from a source of supply whereby upon vaporization of the predetermined quantity, the pressure derived therefrom will force the liquid from the receiving chamber into the boiler.

Another important object is to provide a measuring bucket adapted to be filled with a predetermined quantity of the boiler feed medium after the storage chamber has filled with feed medium to a predetermined level, the bucket after receiving said predetermined quantity being arranged to dump the same rapidly into the vaporizing chamber.

A further object is to utilize the measuring bucket to control a check valve through which the receiving chamber has communication with the low pressure source of the boiler feed medium so that said check valve may be released for closure as the bucket dumps its charge into the vaporizing chamber to the end that the pressure developed for the purpose of forcing the feed medium into the boiler may not be dissipated to said source.

Numerous other objects, advantages and inherent functions of the invention will become apparent as the same is understood from the following description which, taken in connection with the accompanying drawings, discloses a preferred embodiment of the invention.

Referring to the drawings, Fig. 1 is a diagrammatic showing of a refrigerating system of the character illustrated and described in the aforesaid application of William C. Grunow for United States Letters Patent and containing boiler feeding means embodying the present invention;

Fig. 2 is a sectional, somewhat diagrammatic view of a boiler feeding device embodying the present invention;

Fig. 3 is a perspective view of the boiler and boiler feeding device shown in Fig. 1;

Fig. 4 is a sectional view taken substantially along the line 4—4 in Fig. 3, to illustrate the internal construction of the boiler;

Fig. 5 is a sectional view taken substantially along the line 5—5 in Fig. 3, in order to show the

internal arrangement of the boiler feed device; and

Fig. 6 is a perspective view of a measuring bucket forming a part of the boiler feed device.

5 To illustrate our invention we show on the drawings a feeding device 11 for delivering a fluid into a container 13, such as a boiler, at relatively high pressure from a source of supply 15 at relatively lower pressure, and while the invention 10 may have general application, particularly in feeding liquid to boilers, we have shown the device 11 connected in a refrigerating system of the character illustrated in the application of William C. Grunow for United States Letters Patent, Serial No. 144,346, filed May 24, 1937, the 15 same comprising a refrigerating system adapted for operation on the compression-condensation-evaporation cycle, wherein a refrigerating medium, in gaseous condition, is compressed by the 20 pumping means 17 and delivered to a condenser 20, and wherein the refrigerating medium is cooled to liquefy the same at substantially compression pressure. The liquefied medium may then be delivered through suitable pressure controlling equipment, such as a float valve 21, to a relatively low pressure heat absorbing zone shown in the illustrated embodiment as an evaporator 23, in which the liquid refrigerant is permitted to evaporate in order to absorb heat, the 25 resulting vapors produced in evaporators 23 being returned to the suction or low pressure side of the refrigerant compressing means 17, preferably through a check valve 25.

The pumping means comprises jet pumps 19 30 which are actuated by vapor under pressure preferably derived by the application of heat to a suitable medium, which medium may comprise a portion of the refrigerating medium itself. The 35 operation of a refrigerating system by means of jet pumps, as demonstrated in the aforesaid application of William C. Grunow et al. for United States Letters Patent, is feasible providing the refrigerating medium has vapor pressure characteristics such that under normal temperature 40 conditions the refrigerant may be evaporated and condensed within certain pressure differentials commercially maintainable. Such a medium is trichloro-trifluoro-ethane $C_2F_3Cl_3$, commonly known as Carrene No. 3.

45 In a system of the character described, a portion of the condensed refrigerant may be drawn from the condenser and delivered in the boiler 13 and there evaporated to produce vapor under pressure for the actuation of the jet pumps, the 50 liquid delivered in the boiler 13 being there evaporated by the application of heat in any suitable or convenient manner, as by the burning of fuel under the boiler 13, the same being illustrated as a gas burner 27. If desired, the vapor may be 55 thoroughly dried and slightly superheated by passing the same through the coil 29 before delivering it to the jet pumps 19.

The system, of course, may be operated by utilizing a pump actuating medium in the refrigerating medium, providing some means is provided for separating the pump actuating from the refrigerating medium after the same are liquefied in the condenser. Furthermore, it should be clearly understood that the present invention is 60 not necessarily restricted to a boiler feed device for use in refrigerating systems of the character mentioned. At the same time the feeding device of the present invention is particularly well suited for delivering liquid from the condenser, which 65 is at relatively low pressure compared with pres-

sure maintained in the boiler 13, into the boiler, although it will be apparent that the feeding device may be used to deliver any kind of boiler feeding liquid to the boiler.

70 The invention may have application in connection with the boiler of any suitable or preferred construction. As shown for purposes of illustration the boiler comprises a shell having fire tubes 31 heated in any manner, as for example, electrically or by the combustion of gas, oil or any other fuel, the heating device or burner being located as shown at the lower end of the boiler, and the products of combustion, after passing through the tubes 31, are conducted through a flue 33 of suitable construction, in which flue the 15 superheating coil 29 may be arranged.

To deliver liquid from the supply source 15 into the boiler 13, the device 11 is arranged with a chamber 37 adapted to receive liquid from the source through a pipe or conduit 39 with which is 20 associated a valve 47, permitting only one-way liquid flow from the source to the chamber. The device 11 also has a vaporizer 43 adapted, at intervals, to evaporate a predetermined quantity 25 of liquid and thus develop pressure, at least equal to that prevailing in the boiler 13 in order to permit the liquid to enter the boiler and thus feed the same. To this end the chamber 37 is connected to the boiler by means of a pipe or conduit 45, which has a valve 41 permitting only 30 one way liquid flow from the chamber 37 to the boiler.

The vaporizer 43 is connected, preferably, to the top of the chamber 37, as at 49, said connection affording an overflow for liquid from the 35 chamber into the vaporizer after a predetermined quantity or charge of liquid has entered the chamber 37 from the source. The vaporizer is preferably formed as a thick walled element having an appreciable heat storing capacity and the 40 same is continuously heated, either separately as shown in Fig. 2, or by the same source of heat used to heat the boiler 13. As shown in Fig. 1, the vaporizer is a thick walled casting, preferably of metal, having a plurality of fire tubes like the 45 tubes 31 of the boiler. The walls of the vaporizer define a liquid space around the fire tubes and the device may be arranged immediately beneath the boiler with its fire tubes in line with those of the boiler so that the vaporizer is at all times exposed to the hottest parts of the burner 27.

50 As soon as liquid is delivered into the hot vaporizer, it will evaporate and generate pressure which, through the connection 49, is made available to equalize the pressure of the chamber 37 55 with that of the boiler 13, or develop excess pressure in the chamber, thereby causing the liquid to flow from the chamber through the check valve 41, into the boiler. The check valve 41, during this boiler feeding period, of course, prevents the 60 pressure from dissipating to the low pressure source.

65 Incidentally, the heat applied in vaporizing the liquid in the vaporizer 43 is transferred to the boiler feed liquid in the chamber 37 which is thus preheated appreciably as it is forced to the boiler. Thus the heat energy applied to the vaporizer is not entirely lost.

The quantity of liquid required to be charged 70 into the vaporizer in order to develop enough vapor to completely displace all of the liquid from the chamber 37 depends upon the character of the liquid and the amount to be fed into the boiler. The exact quantity required can be easily computed for any desired application, but it is 75

preferable, of course, that the entire amount of liquid be fed into the vaporizer all at substantially the same instant to permit instantaneous development of all of the vapor needed to displace the liquid in the chamber 37. We therefore have provided a measuring bucket 51, positioned to receive overflow liquid, delivered from the chamber 37, until the bucket has received a predetermined quantity or charge, at which instant the bucket is designed to dump its contents into the vaporizer 43. The bucket is of a character adapted, when empty, to hang upright against a stop 53, the center of gravity of the empty bucket being below and at one side (the left side in Fig. 5) of the tilting axis of the bucket. The bucket, however, is designed so that, as it is filled with liquid, the center of gravity of bucket and contents shifts to a point above and to the opposite side (the right side in Fig. 5) of the tilting axis, thereby causing the bucket to tilt and discharge its contents after receiving a predetermined quantity of liquid. The bucket is arranged also to remain in tilted or liquid discharging position, after being initially overbalanced, until all of its contents have discharged, at which time the weight distribution of the material of the bucket causes it to regain its normal position.

After the liquid has been delivered into the boiler by operation of the vaporizer, the vapor remaining in the chamber eventually condenses since the walls of the chamber 37 are at a temperature substantially below the boiling point of the feed medium. Upon condensation reduced pressure conditions are established in the chamber 37, thus permitting the valve 41 to open and liquid to be introduced into the chamber from the source. As soon as low pressure conditions are thus established in the chamber, the check valve 41 is, of course, closed by the higher pressure prevailing in the boiler, thereby preventing backflow from the boiler to the chamber 37 of the feeding device.

In order to accelerate the condensation of residual vapor in the chamber 37, after the delivery of liquid into the boiler, pressure relief means may be provided for establishing communication between the chamber 37 and the source 15 at a point above the level of the liquid therein while the pressure in the chamber 37 is in excess of that at the source 15. The interior of the chamber being exposed to the source, condensation takes place instantaneously and the device is conditioned to receive liquid from the source without undue delay. To this end a relief valve 117 may be connected with pressure responsive means adapted to open the same when pressure in the chamber falls below a predetermined value. As shown in Fig. 5, the valve 117 comprises an element pivoted as at 55 to swing toward and away from a seat 57 connected with a conduit 119 which leads to the upper portion of the condenser 20. The valve may be provided with a finger 59 in position to engage a rack 61 operatively connected with pressure responsive means 63 adapted to shift the rack in a direction to open the valve when pressure within the chamber 37 falls below a predetermined value. In the embodiment shown in Fig. 5, the pressure responsive means 63 comprises a bellows, the outer end of which is anchored in and sealed to the walls of the chamber with the interior of the bellows exposed to atmosphere, while the other end of the bellows is sealed upon the disk-like head 69 of a stem 67 to which is pivoted the rack, as at 65.

As a matter of manufacturing convenience and

simplicity of design, we prefer to form the device as a plurality of separate parts, including a preferably cylindrical casting forming the chamber 37; a generally cylindrical casting 13 forming a part of the vaporizer and comprising a housing 5 for the bucket 51, preferably separate from but connecting with the heated portions of the vaporizer 43, as by the pipe 75; a preferably cylindrical casting 71 forming a housing for the valve 117 and its actuating mechanism, said housing 10 connecting with the chamber 37; and a manifold plate 79.

The bottom of the chamber 37 conveniently may be closed by means of a plug 71, by means of which the conduits 39 and 45 may be connected 15 with the chamber and in which plug, if desired, the valves 41 and 47 may be arranged. The upper end of the chamber may be connected to the manifold plate 79 which is or may be formed with a bore 81, connected with the chamber 37, and a 20 cavity 83 communicating with the bucket housing 13. The bore 81 and cavity 83 are connected by channels forming the connection 49, there being preferably an upper large channel 149 to permit free passage of vaporized medium to the 25 chamber 37, and a lower relatively smaller channel 249 to permit liquid to overflow from the chamber 37 and enter the bucket 51. The plate 79 may be drilled as at 85 to permit formation of the channels 149 and 249 by drilling and the 30 opening then closed by the plug 87.

The plate 79 may be secured, as by bolting or otherwise, upon the castings 37 and 13, and a cover 89 may be provided on the plate to close the upper end of the bore 81 and the chamber 37. 35 The cover 89 may comprise the bottom of the valve housing 71 which, if desired, may be secured directly to the plate 79 with the housing 71 in direct communication with the chamber 37. We prefer to use a short pipe 91 to connect the 40 housings.

The valve housing 71, in the form shown, has a bottom in which one end of the pipe 91 is secured, and the top is closed by a removable cover. The valve seat 57 may be formed, conveniently, in a fitting adapted to be threaded in an opening in the side walls of the housing 71, the conduit 119 being fastened to the outer end of the fitting. The bellows 63 may be mounted on a plate 93 which is clamped, by a holding plate 95, in a lateral opening in the walls of the housing 71. The holding plate may be formed with openings 97 to expose the bellows to atmosphere and may carry an adjusting screw 99 accessible from without the housing to vary the tension on a spring 101 which bears at one end upon a shoulder 103 on the stem of the screw. The spring extends through an opening in the plate 93 and bears against the head 69 of the valve opening linkage in order to aid atmospheric pressure in 60 opening the valve 117. The plate also holds in place a collar 105 which serves to limit the movement of the head 69 under the influence of the spring and atmosphere. The screw 99 may have a projection 107 extending within the spring 101 65 to support the same against lateral buckling when in compression and also to limit travel of the bellows to prevent crushing.

The collar 105 may carry spring means 109 to urge the rack 61 toward the detent 59, and it 70 will be seen that the spring 101 may be adjusted by the screw 99 to urge the valve 117 open and thus permit the same to open when the pressure in the chamber 37 (which is also the pressure in the housing 71) falls to a predetermined value, 75

which, of course, may be substantially in excess of atmospheric pressure.

As liquid from the source 15 enters and fills the housing 37 and, after reaching the overflow conduit 249, fills the bucket 51, it is desirable, if not necessary, to release the valve 117 so that it may close immediately upon the dumping of the bucket 51 and consequent generation of boiler feeding vapor pressure in the chamber 37. To ensure that the valve will be free to close, the bucket is suspended in a bracket 110 which, in turn, is hung on one end of a lever 111 in the cavity 83. The lever 111 may be fulcrumed, as at 113, in the channel 149; and has its other end 15 extending in the bore 81 and connected with the rack 61 by means of a connecting rod 115 which may extend from the end of the lever arm in the cavity 81, through the pipe 91, into the housing 17. The spring 109 is adapted to hold the rack down when the bucket 51 is empty and while it is filling. Just before dumping, the weight of liquid in the bucket, however, is sufficient to tilt the lever 111 and raise the rack 61 from the detent 59, thus releasing the valve 117. The valve is so weighted that it will move toward closed position by gravity and closely overlie the seat 57 so that when the bucket discharges its load into the vaporizer the valve 117 may be snapped tightly shut immediately upon the vaporization of the dumped liquid.

The liquid feeding device of our present invention may, of course, be applied to the delivery of any kind of medium required to be transferred from a supply source to a delivery station at 35 relatively higher pressure and the invention consequently is not necessarily restricted to the delivery of liquid in a boiler from a condenser, nor to the feeding of boiler feed medium from a condenser forming a part of a refrigeration system of the character mentioned. The device of the present invention, however, is particularly well adapted for use in feeding an evaporable medium to a boiler used in generating vapor for the operation of jet pump compressors in a 45 compression-expansion-evaporation refrigerating system.

The feeding device of the present invention has the advantages of compactness, efficiency and silence in operation, and affords an efficient 50 means for delivering a liquid to a boiler. The invention, of course, has general application, although it is particularly well adapted for use in connection with refrigerating systems of the character heretofore mentioned, and when so applied makes feasible the provision of a commercially satisfactory refrigeration system of the compression-expansion-condensation type for 55 operation by gas or other fuel.

It is thought that the invention and its 60 numerous attendant advantages will be fully understood from the foregoing description, and it is obvious that numerous changes may be made in the form, construction and arrangement of the several parts without departing from the 65 spirit and scope of the invention or sacrificing its attendant advantages, the forms herein disclosed being preferred embodiments for the purposes of illustrating the invention.

What we claim as new and desire to secure by 70 Letters Patent of the United States is as follows:

1. The method of delivering an evaporable medium to a boiler serving the jet compressors in a compressor-condenser-expander refrigerating system, which consists in withdrawing refrigerant from the condenser of the system to an

intermediate zone, heating a portion of the withdrawn refrigerant to develop vapor under pressure in excess of that in the boiler, and using the vapor thus produced to deliver the remainder of the withdrawn refrigerant into the boiler and alternately of said delivery step reducing the pressure to permit supplying of refrigerant to said intermediate zone from the low pressure supply by establishing vapor connection of the intermediate zone with the said low pressure supply. 10

2. The method of operating a compressor-condenser-expander refrigerating system employing jet compressors actuated by a boiler to circulate the refrigerant in the system which 15 comprises withdrawing liquid refrigerant from the condenser of the system to an intermediate zone, heating a portion of the refrigerant thus withdrawn to develop vapor under pressure in excess of that which prevails in the boiler using 20 the vapor pressure thus produced to deliver the remainder of the withdrawn liquid into the boiler, heating the liquid in the boiler to produce vapor under pressure, and returning the same to the condenser of the system through the jet 25 pumps whereby to exert a pressure differential in remote portions of the system and thus cause the same to operate and alternately of said delivery step reducing the pressure to permit supplying of refrigerant to said intermediate zone 30 from the low pressure supply by establishing vapor connection of the intermediate zone with the said low pressure supply.

3. The method, as set forth in claim 1, where- 35 in the said heated portion of the withdrawn refrigerant is at least partially transferred to the remaining portions of the liquid and serves to preheat the same prior to the introduction thereof into the boiler.

4. A fluid feed device comprising receiving 40 means to receive a fluid medium from a relatively low pressure supply source, means to evaporate a part of the received medium and generate vapor pressure in said receiving means whereby to force the remainder of the medium, 45 as a charging unit, into a delivery zone in which the prevailing pressure is higher than that at the supply source, including a check valve between the receiving means and the source and between the delivery zone and the receiving 50 means, valve operating means, operable in response to decrease in pressure in the receiving means after expulsion of medium to the delivery zone, and a valve arranged between the supply source and the receiving means for controlling 55 communication between said supply source and receiving means, said valve and valve operating means being operatively associated to open said valve when the operating means is operated for equalizing the pressure in the supply source and 60 the receiving means.

5. A fluid feed device comprising receiving 65 means to receive a fluid medium from a relatively low pressure supply source, means to evaporate a part of the received medium and generate vapor pressure in said receiving means whereby to force the remainder of the medium, as a charging unit, into a delivery zone in which the prevailing pressure is higher than that at the supply source, including a check valve be- 70 tween the receiving means and the source and between the delivery zone and the receiving means, valve operating means, operable in response to decrease in pressure in the receiving means after expulsion of medium to the delivery 75

zone, and a valve arranged between the supply source and the receiving means for controlling communication between said supply source and receiving means, said valve and valve operating means being operatively associated to open said valve when the operating means is operated for equalizing the pressure in the supply source and the receiving means, including means to adjust the valve operating means to release the valve at a predetermined pressure.

6. A fluid feed device comprising receiving means to receive a fluid medium from a relatively low pressure supply source, means to evaporate a part of the received medium and generate vapor pressure in said receiving means whereby to force the remainder of the medium, as a charging unit, into a delivery zone in which the prevailing pressure is higher than that at the supply source, including a check valve between the receiving means and the source and between the delivery zone and the receiving means, valve operating means, operable in response to decrease in pressure in the receiving means after expulsion of medium to the delivery zone, and a valve arranged between the supply source and the receiving means for controlling communication between said supply source and receiving means, said valve and valve operating means being operatively associated to open said valve when the operating means is operated for equalizing the pressure in the supply source and the receiving means, said valve operating means being operable in response to the differential in pressure within and without the receiving means.

7. A fluid feed device comprising receiving means to receive a fluid medium from a relatively low pressure supply source, means to evaporate a part of the received medium and generate vapor pressure in said receiving means whereby to force the remainder of the medium, as a charging unit, into a delivery zone in which the prevailing pressure is higher than that at the supply source, including a check valve between the receiving means and the source and between the delivery zone and the receiving means, valve operating means, operable in response to decrease in pressure in the receiving means after expulsion of medium to the delivery zone, and a valve arranged between the supply source and the receiving means for controlling communication between said supply source and receiving means, said valve and valve operating means being operatively associated to open said valve when the operating means is operated for equalizing the pressure in the supply source and the receiving means, said valve operating means being operable in response to the differential in pressure within and without the receiving means, and including adjustable spring means normally biasing said valve operating means toward valve opening position.

8. A fluid feed device comprising intermediate zone receiving means to receive a fluid medium from a relatively low pressure supply source, means to evaporate a part of the received medium and generate vapor pressure in said receiving means whereby to force the remainder of the medium, as a charging unit, into a delivery zone in which the prevailing pressure is higher than that at the supply source, said evaporating means comprising a heated vaporizing chamber connected to the receiving means to receive and vaporize a quantity of medium after a predetermined amount of the medium has entered the receiving means from the source, and means

operable in response to a drop in pressure in the receiving means to reduce, alternately of said delivery step, the pressure in the receiving means to permit supplying of refrigerant to said intermediate zone from the low pressure supply by establishing vapor connection between the intermediate zone and the low pressure supply.

9. A fluid feed device comprising intermediate zone receiving means to receive a fluid medium from a relatively low pressure supply source, means to evaporate a part of the received medium and generate vapor pressure in said receiving means whereby to force the remainder of the medium, as a charging unit, into a delivery zone in which the prevailing pressure is higher than that at the supply source, said evaporating means comprising a heated vaporizing chamber connected to the receiving means to receive and vaporize a quantity of medium after a predetermined amount of the medium has entered the receiving means from the source, means to deliver a measured quantity of the medium into said vaporizing chamber as an actuating charge, and means operable in response to a drop in pressure in the receiving means to reduce, alternately of said delivery step, the pressure in the receiving means to permit supplying of refrigerant to said intermediate zone from the low pressure supply by establishing vapor connection between the intermediate zone and the low pressure supply.

10. A fluid feed device comprising intermediate zone receiving means to receive a fluid medium from a relatively low pressure supply source, means to evaporate a part of the received medium and generate vapor pressure in said receiving means whereby to force the remainder of the medium, as a charging unit, into a delivery zone in which the prevailing pressure is higher than that at the supply source, said evaporating means comprising a heated vaporizing chamber connected to the receiving means to receive and vaporize a quantity of medium after a predetermined amount of the medium has entered the receiving means from the source, a self-righting measuring bucket in position to receive a predetermined quantity of the medium as overflow from the receiving means and dump the same into the vaporizing chamber, and means operable in response to a drop in pressure in the receiving means to reduce, alternately of said delivery step, the pressure in the receiving means to permit supplying of refrigerant to said intermediate zone from the low pressure supply by establishing vapor connection between the intermediate zone and the low pressure supply.

11. A fluid feed device comprising receiving means to receive a fluid medium from a relatively low pressure supply source, means to evaporate a part of the received medium and generate vapor pressure in said receiving means whereby to force the remainder of the medium, as a charging unit, into a delivery zone in which the prevailing pressure is higher than that at the supply source, said actuating means comprising a heated vaporizing chamber connected to the receiving means to receive and vaporize a quantity of medium after a predetermined amount of the medium has entered the receiving means from the source, a check valve between the source and said receiving means and opening toward the latter to seal the same from the source when vapor pressure is developed in said receiving means, valve operating means operable in response to decreasing pressure in said

receiving chamber after expulsion of medium therefrom to the delivery zone, a valve arranged between the supply source and the receiving means for controlling communication between said supply source and receiving means, said valve and valve operating means being operatively associated to open said valve when the operating means is operated for equalizing the pressure in the supply source and the receiving means, and means to deliver a quantity of the medium into the vaporizing chamber as an actuating charge, and in cooperation with said valve actuating means to release said valve for closure prior to the delivery of said actuating charge into said vaporizing chamber.

12. A fluid feed device comprising receiving means to receive a fluid medium from a relatively low pressure supply source, means to evaporate a part of the received medium and generate vapor pressure in said receiving means whereby to force the remainder of the medium, as a charging unit, into a delivery zone in which the prevailing pressure is higher than that at the supply source, said actuating means comprising a heated vaporizing chamber connected to the receiving means to receive and vaporize a quantity of medium after a predetermined amount of the medium has entered the receiving

means from the source, a check valve between the source and said receiving means and opening toward the latter to seal the same from the source when vapor pressure is developed in said receiving means, valve operating means operable 5 in response to decreasing pressure in said receiving chamber after expulsion of medium therefrom to the delivery zone, a valve arranged between the supply source and the receiving means for controlling communication between 10 said supply source and receiving means, said valve and valve operating means being operatively associated to open said valve when the operating means is operated for equalizing the pressure in the supply source and the receiving 15 means, and a self-dumping measuring bucket in position to receive a predetermined quantity of the medium as overflow from the receiving means and to dump the same into the vaporizing chamber as an actuating charge, said bucket 20 being operatively connected with said valve operating means to release said valve for closure when the bucket contains a quantity of liquid just short of that required to dump the bucket.
